Primary Examiner—Antoine Duval Davis
Attorney, Agent, or Firm—Jules Jay Morris; David Barron; Terrence Martin[57] **CLAIM**

The ornamental design for a housing for a portable gas analyzer, as shown and described.

DESCRIPTION

FIG. 1 is a perspective view of a housing for a portable gas analyze embodying our new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear elevational view thereof;

FIG. 7 is a bottom plan view thereof; and,

FIG. 8 is a perspective view of the housing as positioned for use by an operator.

Objects shown in broken lines shown in FIG. 8 are for illustrative purposes only and form no part of the claimed design.
